APPARATUS FOR PLATING CHROMIUM

Charles Frederick Geese, Old Greenwich, Conn.,
assigner to Time, Incorporated, New York,
N. Y., a corporation of New York

Application December 17, 1949, Serial No. 133,545

3 Claims. (Cl. 204—224)

1

The present invention relates to apparatus for plating chromium and like metals, and embodies more specifically an improved form of plating apparatus by means of which metals, such as chromium, may be spot plated, that is, plated upon surfaces that are extremely small in area.

In conventional plating operations, the surface to be plated is immersed in a plating solution and made the positive terminal of an electrical circuit while the metal to be plated upon the surface is made the negative terminal. The plating occurs over the entire submerged surface except such portions as may be staged out by means of a suitable coating that resists the passage of current. Where a relatively small amount only of a surface is to be plated, difficulty is experienced in staging out the surface that is not to be plated, and it is an object of the present invention to provide an apparatus and also a method by means of which metallic plating operations may be carried on in extremely limited areas.

A further object of the invention is to provide an apparatus and method of the above character wherein spot plating of metals, such as chromium, may be accomplished without disturbing adjacent surfaces or requiring treatment thereof to protect them against injury.

Yet another object of the invention is to provide an apparatus and method of the above character wherein metals, such as chromium, may be plated upon desired surfaces without requiring such surfaces to be immersed in a plating solution.

Further and other objects of the invention will be apparent as it is described in greater detail in connection with the accompanying drawings, wherein

Figure 1 is a schematic view illustrating elements of a plating apparatus constructed in accordance with the present invention;

Figure 2 is a view in longitudinal cross-section, taken on the line 2—2 of Figure 1, showing a spot plating mechanism constructed in accordance with the present invention;

Figure 3 is a bottom view of the device shown in Figure 2; and

Figure 4 is a view in longitudinal cross-section, taken on the line 2—2 of Figure 1, showing the lower portion of an alternate embodiment of the spot plating mechanism constructed in accordance with the invention.

Referring to the above drawings, 10 indicates a surface upon which plating is to be effected in limited areas, this surface constituting any element such, for example, as a printing plate. The plate is connected to the negative terminal of a

2

battery 11 or other suitable source of electric current through a clip 12 and wire 13. The positive terminal of the battery is connected through a wire 14 to a plating tool 15 which may be formed at its upper end with a bushing 16 through which the wire 14 extends and with an intermediate wall 17. A cup-shaped terminal 18 is carried by the wall 17 and connected to the wire 14, as illustrated in Figure 2.

The tool 15 is formed of a casing 19 that may comprise nylon or some similar substance that is impervious to the compounds that might be used as plating solutions, as hereinafter mentioned. A head 20 is formed with a shoulder portion 21

15 within which the end of the casing 19 fits, the fit either being accomplished by a threaded connection or by press fit against a circumferential wall 22 that may have a slight taper toward the axis of the head and away from the shoulder 21.

20 Axially of the head 20, a threaded shaft 23 is secured, the axial position of the shaft with respect to the head being variable by turning the shaft therein. At the lower end of the head 20 a conically shaped tip 24 is secured, the tip being

25 slotted at 25 and terminating in an opening 26 at the small end thereof. An anode 27 in the form of a metallic wire is carried by the shaft 23 and extends to a point adjacent the opening 26, the size of the opening 26 and the slots 25 being such that a plating solution 28 may be retained within the tip without flowing therefrom by gravity. For example, the width of the slots 25 may preferably be in a range of from .006" to .010". Even though slots of this size will not

30 permit the free flow of the plating solution 28 by gravity, the slots 25 will tend to feed the plating solution 28 to the opening 26. The space within the tip and above the plating solution 28 may either be vented to the atmosphere by means of a vent 29 of sufficiently small size as shown in Figure 2 or a duct 30 as shown in Figure 4 may be formed therein communicating with the circumferential portion 22 so that, when the point is dipped in the plating solution, the latter fills

40 the space within the tip, and the air is exhausted through the duct 30, the casing 19 previously having been removed. When the casing 19 is secured in the position illustrated in Figure 4, the duct 30 is closed, and the plating solution 28

45 more effectively maintained within the tip 24. Under these conditions, the slots 25 will permit gases formed by the electrolytic reaction of the plating operation to escape without blocking the opening 26 and interrupting the plating.

50 55 In operation, the axial position of the anode

27 is suitably adjusted by rotation of the shaft 23 to give the desired spacing of the tip of the anode 27 from the aperture 26. With the electrical circuit connected as illustrated in Figure 1, the opening 26 of the tip 24 is moved against the surface of the element 10 and over the surface in accordance with the areas upon which plating is to be accomplished. The plating tool thus enables minute areas of the element 10 to be plated without disturbing the areas of the element that are not to be plated.

The invention is particularly useful in connection with the manufacture of lithographic printing plates wherein chromium is applied to the portions of the plates which are to be water receptive and ink repellent. The metal of the plate proper (which carries the ink to be printed) may be copper. It frequently happens that after plates of this character have been manufactured, certain corrections must be performed by plating in chromium on areas that have not been properly plated during the manufacture of the plate. These areas are frequently extremely small, and it is extremely difficult to plate them without adding additional chromium plating to the previously plated portions, or to other areas in which the base metal (such as copper) is to be preserved. It will be apparent that the apparatus is suitable for plating metals other than chromium simply by selecting the desired plating solution. The anode 27 may be formed of the metals which are to be plated, in which event, different shafts 23 with the appropriate anodes 27 are utilized for plating different metals. In operation, the tool 15 is used somewhat similarly to the way in which a pen is used. The tip may be dipped into the plating solution in order that a quantity of the solution may enter the tip as illustrated in Figure 2.

The material of which the metallic contact wire is formed quite naturally depends upon the particular plating operation that is being carried out. For example, if chromium is being plated, the material of the wire anode might be either platinum or stainless steel. In operations involving the plating of other materials, such as silver, nickel, gold, copper, zinc, etc., the contact could and should be of the correspondingly appropriate material, in accordance with recognized plating operations. It will also be understood that the size or area of the surface that is plated need not be relatively small. The operating end of the device may be formed with a relatively wide slot

and an appropriately formed anode in order that more substantial areas may be plated upon one application or operation of the apparatus.

While the invention has been described with specific reference to the accompanying drawings, it is not to be limited save as defined in the appended claims.

I claim:

1. Plating apparatus for spot electroplating conducting surfaces comprising, a rigid non-conductive tip formed with a hollow portion therein providing a reservoir for plating solution and having a capillary opening at the extremity thereof connecting with the hollow portion for gradually releasing the solution upon movement of the extremity of said tip against a surface to be plated, and an elongated anode within said tip having an end adjacent the opening, said extremity of said tip having slots intersecting and extending away from said capillary opening to prevent gases formed by electrolysis from blocking the capillary opening.
2. Plating apparatus for spot electroplating conducting surfaces comprising a rigid hollow enclosed conically-shaped non-conductive tip adapted to retain a supply of plating solution therein, having a capillary opening at the apex thereof for gradually releasing the solution upon movement of said tip against a surface to be plated, and provided with a pressure equalizing vent, opening into said enclosed conically-shaped tip, and an elongated anode within said tip having an end extending into the opening, said tip being provided with slots intersecting and extending away from said capillary opening.
3. Plating apparatus according to claim 2 wherein the elongated anode comprises a wire substantially coaxial with the non-conductive tip.
